CLAMP

Charles B. Sparks, Youngstown, Ohio

Application March 27, 1937, Serial No. 133,452

2 Claims. (Cl. 24—125)

The invention relates to clamps and more especially to cable, rope or rod clamps.

The primary object of the invention is the provision of a clamp of this character, wherein runs of cable, rope, rods or the like can be readily and easily gripped to avoid relative movements thereof at the point of the clamp, being no liability of slippage and a firm and secure hold will be had thereon.

10 Another object of the invention is the provision of a clamp of this character, wherein the same is of novel construction so that it may be easily applied for the gripping of cables, wires, rods or ropes without damage thereto and also maintaining the same in fixed relation to each other.

20 A further object of the invention is the provision of a clamp of this character, wherein rods, ropes, cables or wires may be firmly and securely held secure with respect to each other irrespective of the size thereof within reasonable limits and a positive and firm grip will be assured.

25 A still further object of the invention is the provision of a clamp of this character, which is extremely simple in construction, thoroughly reliable and effective in its operation, strong, durable, and inexpensive to manufacture and install.

With these and other objects in view, the invention consists in the features of construction, combination and arrangement of parts as will be 30 hereinafter more fully described, illustrated in the accompanying drawing, which discloses the preferred embodiment of the invention and pointed out in the claims hereunto appended.

In the accompanying drawing:

35 Figure 1 is a side elevation of a clamp constructed in accordance with the invention applied.

Figure 2 is a view similar to Figure 1 looking toward the other side thereof.

Figure 3 is a top plan view.

40 Figure 4 is a bottom plan view.

Figure 5 is a sectional view on the line 5—5 of Figure 1 looking in the direction of the arrows.

Figure 6 is a vertical longitudinal sectional view through the clamp.

45 Similar reference characters indicate corresponding parts throughout the several views in the drawing.

Referring to the drawing in detail, the clamp A constituting the present invention comprises a 50 pair of opposed clamping heads 10 and 11, respectively, each having a flat side edge 12 and an opposite fluted edge 13, respectively, which latter provides perforated ears 14. These ears 14 accommodate the arms of substantially U-shaped 55 clips 15 each formed with an inwardly angled

closed end 16 and the arms of said clips are adjustably fitted with nuts 17.

Interposed between the heads 10 and 11 is a 5 spacer block or plate 18, it having the perforated ears 19 for accommodating the arms of one of the clips 15 and disposed between this block or plate 18 and the heads 10 and 11 next thereto are cables 20 to be clamped, these being adapted for seating within distorted channels or grooves 21 provided in the faces adjacent to each other of the said 10 heads 10 and 11 and block or plate 18.

Formed on the head 10 medially at the straight edge 12 thereof is a hook-like keeper nose 22 to be saddled by the closed end 16 of one of the clips 15 while formed on the head 10 medially of its 15 straight edge 12 is an eye 23 loosely accommodating the end 16 of the other clip 15.

The edge of the block or plate 18 opposite the ears 19 is formed with clearance recesses 24 for the arm of the clip 15 next thereto. 20

The cables 20 or the equivalent such as rods, 25 ropes or wires, will be firmly and securely clamped when seated between the heads 10 and 11 and the block or plate 18 on the working of the nuts 17 inwardly on the arms of the clips 15 engaged in the manner as heretofore stated with the keeper 22 and the eye 23, respectively.

The clips 15 are disposed along side of the heads 10 and 11, these being reversely disposed to have the ears 13 of one at one side and the 30 ears 13 of the other head at the other side with respect to said cables, the clips being on opposite sides of the cables.

There is no possibility of the slipping of the 35 cables when engaged in the clamp and the easy and quick application of the latter is effective and when such cables are clamped they will not be damaged but will be held against relative movements with respect to each other.

What is claimed is:

1. A clamp of the character described comprising opposed heads having seats in their inner faces, a spacer block between said heads and having seats registering with the seats in said head, the seats being distorted, lateral reversely disposed perforated ears on said heads, perforated ears on the spacer block and registering with the ears of one head, double armed substantially U-shaped clips passed through the perforated ears in the heads, one of the clips being passed through 50 the perforated ears on the block, an eye loosely connecting one clip with one head, and a keeper on the other head and engaged by the other clip. 55

2. A clamp of the character described comprising opposed heads having seats in their inner

faces, a spacer block between said heads and having seats registering with the seats in said head, the seats being distorted, lateral reversely disposed perforated ears on said heads, perforated ears on the spacer block and registering with the ears of one head, double armed substantially U-shaped clips passed through the perforated ears

in the heads, one of the clips being passed through the perforated ears on the block, an eye loosely connecting one clip with one head, a keeper on the other head and engaged by the other clip, and adjustable nuts fitting the clips and working 5 against the heads.

CHARLES B. SPARKS.
